UNITED STATES PATENT OFFICE.

FREDERICK SCHUELER, OF LA SALLE, ILLINOIS.

CUT-OFF.

SPECIFICATION forming part of Letters Patent No. 325,449, dated September 1, 1885.

Application filed August 6, 1884. (No model.)

To all whom it may concern:

Be it known that I, FREDERICK SCHUELER, a citizen of the United States, residing at La Salle, in the county of La Salle and State of Illinois, have invented a new and useful Improvement in Cut-Offs, of which the following is a specification, reference being had to the accompanying drawings.

My invention relates to a cut-off for controlling the direction of water; and it has for its object to provide a device by which the position of the valve or cut-off may be determined from the position occupied by its handle.

15 A further object of the invention is to provide a thoroughly water-tight valve and one that will be held in position by its own weight.

20 A further object of the invention is to provide a cut-off which shall be cheap and simple in its construction, effective in its operation, and durable in its use.

25 With the above and other objects in view, the invention consists in the improved construction and combinations of parts herein-after fully described, and pointed out in the claims.

In the drawings, Figure 1 is a perspective view of a cut-off constructed in accordance 30 with my invention. Fig. 2 is a longitudinal vertical section of the same, and Fig. 3 is a transverse vertical section.

35 In the accompanying drawings, in which like letters of reference indicate corresponding parts in all the figures, A represents the shell or casing, which, as shown, is semicircular in form. Upon the upper side of this casing A is provided a hole or opening, B, which is provided with an annular flange 40 forming a mouth-piece, C. Near each end of the casing, upon the lower side thereof, are provided holes or openings b, which, like the opening B, are each provided with an annular flange to form mouth-pieces D and E.

45 Extending upwardly inside the casing, between the two holes or openings, is a partition, F, which extends upwardly a short distance, and connects the two side walls of the shell or casing. The upper end of said 50 partition is rounded, as shown.

G represents the cut-off, which is hollowed

out at its lower end. This hollowed-out or recessed end is adapted to fit upon the upper end of the partition, and has bearing upon the same, so that it can be turned in either 55 a right or left direction. The side walls of the cut-off or valve are made slightly concave, the curvature commencing from the upper end,

H represents flanges which are secured to 60 the ends of the cut-off or valve, said flanges being quadrantal in form, and so arranged that when the valve is operated to close either of the openings D or E one of the ends of both of said flanges will rest upon the floor 65 of the shell or casing and prevent further movement of the valve.

I represents a slot or opening formed upon the side of the shell or casing. This slot or opening is closed by one of the flanges H, 70 and secured to said flange and extending through said slot is a finger-piece, J, for operating the valve.

In operation, supposing the valve to be in the position shown in Fig. 1, to turn the 75 cut-off or valve, the finger-piece is moved to the opposite end of the slot, which changes the flow of water from the pipe D to the pipe E. The valve will be held in place against any movement by its own weight. 80

It will be seen from the above description that a cut-off constructed in accordance with my invention is simple, may be manufactured and supplied at a slight cost, and its operation is thoroughly effective, and that it is strong 85 and durable.

Having fully described my invention, what I claim as new, and desire to secure by Letters Patent, is—

The semicircular-shaped casing A, having 90 a flat base, and inlet and outlet openings connecting with the latter at each end, in combination with the partition F, extending upward from the base of the casing between the openings, the valve or cut-off G, turning on 95 a bearing at the upper end of the latter, and having its upper end working against the curved inner face of the casing, quadrantal-shaped flanges H, secured to and projecting from each side of the cut-off or valve, a slot, I, 100 in one side of the casing, and a finger-piece, J, working through the slot and connected

to the valve, the said flanges covering the slot and adapted to abut at their ends against the floor or base of the casing over either the inlet or outlet openings, so as to limit the 5 movement of the valve, for the purpose set forth.

In testimony that I claim the foregoing as

my own I have hereunto affixed my signature in presence of two witnesses.

FREDERICK SCHUELER.
